Pierre Barnes
ATTORNEY

UNITED STATES PATENT OFFICE.

SERN P. WATT, OF SEATTLE, WASHINGTON.

WASHING MACHINE.

Application filed March 26, 1924. Serial No. 702,014.

To all whom it may concern:

Be it known that I, SERN P. WATT, a citizen of the United States, residing at Seattle, in the county of King and State 5 of Washington, have invented certain new and useful Improvements in Washing Machines, of which the following is a specification.

This invention relates to washing machines and its object is the provision of a machine of this character which will be simple and convenient to use and will serve to effectively wash clothes or other fabrics without subjecting the same to wear by rubbing or pounding.

More specific objects and advantages of the invention will appear in the following specification.

The invention consists in the novel construction, adaptation and combination of parts hereinafter described and claimed.

In the accompanying drawing,

Figure 1 is a side elevation, partly in section, of a washing machine embodying my invention. Fig. 2 is a transverse section of the machine taken substantially on line 2—2 of Fig. 1. Fig. 3 is a section on line 3—3 of Fig. 1 with a portion of the perforated floor broken away to disclose the 30 partition or baffle members. Figs. 4 and 5 are detail sectional views of the fluid impeller with the shoe element thereof shown in its lower and upper positions respectively. Fig. 6 is a fragmentary elevation 35 of the machine, partly in section, said view being taken from the side of the machine opposite that in which it is illustrated in Fig. 1.

In said drawing, the reference numeral 40 10 represents, generally, a shell or casing which is divided by a partition, consisting of two baffle members 11 and 12 to provide an upper receptacle or chamber 13, and a lower receptacle 14, hereinafter designated as the sump. The chamber is designed to receive the clothes to be washed and may be of any suitable size or shape.

The sump 14 which serves as a reservoir for the washing fluid—water or suds—is of 50 suitable size and of a semi-cylindrical shape as shown. Formed or provided at the bottom of said sump is a gutter 15 disposed transversely of the machine and having an outlet 16 provided with a valve 17.

Extending upwardly from said partition at about the midwidth of the tub is a wall

18 which cooperates with shelf elements 19 of the casing to support a perforated floor 20.

The baffles 11 and 12 are preferably horizontal and of widths to extend from the wall 18 at the center of the casing to the opposite side walls 21 and are each of approximately one-half the length of the bottom of the chamber. Said baffles are furthermore disposed one at the front and the other at the rear of the casing as shown in Fig. 3 so as to afford openings or passages A and B disposed in diagonal relation with respect to the bottom of the chamber 70 13. These passages, it is to be noted, provide communication between the front and rear portions respectively of the sump with the spaces at opposite sides of the wall 18 below the floor including cavities A¹ 75 and B¹ between the baffles 11, 12 and the floor 20.

Rigidly secured to the opposite side walls of the casing are reinforcing plates 22 which are provided adjacent their upper ends with 80 axially aligned trunnions 23 which are journaled in bearing boxes 24 provided on the machine frame 25 so that the casing will oscillate freely thereon.

Subjacent to said trunnions and parallel 85 with the axis thereof, the plates 22 are formed to provide journal bearings for a shaft 26 which is located to be concentric of the arcuate wall 27 of the sump 14. Said shaft extends transversely through the 90 sump and serves as a fulcrum for a blade 28 provided within the sump.

This blade, hereinafter termed the impeller, is of a length slightly less than the 95 distance between the side walls 29 of the sump and of a depth to extend within a short distance of the arcuate wall 27 of the sump. As best shown in Figs. 4 and 5, the impeller is formed or provided at its lower edge with oppositely disposed 100 flanges 30 which serve as hanger elements to support a tubular shoe 31 of an oblong shape in transverse section. The width of the shoe, preferably, is somewhat greater than the maximum width of the gutter 15, 105 and is prevented from entering the latter by means of the impeller flanges 30.

Buttons, pins or other articles falling into the sump are carried by the impeller into 110 said gutter, the relative upward movement of the shoe with respect to the blade permits the impeller to pass over an article

even though the latter be upturned into the path of the shoe should the article fail to enter fairly into the gutter. The shaft end which protrudes from the casing serves 5 as a crank pin which is connected by a connecting rod 33 with the pin 34 of a crank arm 35 of a shaft 36.

The effective length of the crank arm 35 is less than the distance between the axis 10 of the trunnions 23 and that of the shaft 26.

Rigidly mounted upon the crank shaft 36 is a worm wheel 37 which is rotated by 15 a worm 38 whose shaft 39 carries a pulley 40 which is rotated by means of an endless belt 41 from a driving pulley 42 of a motor 43 secured to the machine frame.

Exteriorly of the casing, the impeller shaft 26 has rigidly secured thereto a crank arm 44 whose axis is disposed in a plane 20 with the axis of the blade 28 as represented in Figs. 1 and 6. The pin 45 of the crank arm 44 is connected by a rod or link 46 with a pin 47 secured to a bracket element 48 of the frame. 49 represents a housing 25 for the worm and worm wheel above mentioned.

The operation of the invention is as follows: The material to be washed is placed 30 in the chamber 13 and sufficient washing fluid to secure the proper action is supplied through said chamber into the sump compartment 14 of the machine.

The motor 43 is then started to effect the rotation of the crank shaft 36 whereby motion 35 is imparted through the connecting rod 33 to the shaft 26 for oscillating the casing 10.

The connecting rod 33, it is to be noted, 40 effects a reciprocatory arcuate travel to the shaft 26 which by reason of the connection of the latter to the crank arm 44 which in turn is connected by the link 46 to a stationary pin 47 causes the impeller to be swung in a direction opposite to that in 45 which the casing is oscillated.

The relative motions of the casing and the impeller will be understood from an inspection of Fig. 6 in which it is assumed 50 that the casing is moving in the direction indicated by arrow C the resultant motion of the impeller will be that indicated by direction arrow D.

Under such conditions the water or suds 55 in the sump is caused to surge upwardly at the front and rear but since the baffles 11 and 12 successively obstruct the fluid, the latter can only ascend through the passages A and B alternately at opposite sides of the sump.

These passages A and B, moreover, by 60 communicating with the cavities A¹ and B¹, respectively, cause the fluid to be conducted and delivered through the perforated floor 20 at the right and left hand sides, alternately, of the wall 18.

By such devices the fluid is forced upwardly through the material at one side of the machine and sucked downwardly through the material at the other side of the machine during one stroke of the connecting rod 33 and vice versa during the next following stroke of the connecting rod, and so on, to produce a most effective and rapid washing operation. The efficiency of the washer being largely due to the peculiar 70 positioning of passages diagonally of each other at opposite sides of the wall 18 and at opposite ends of the respective baffles and cavities 11 and 12, which causes the washing water to act against the material and at 75 different portions thereof with simultaneously applied suction and propulsion effects. Such actions of the water with respect to the material acts continuously during the operation of the machine in changing 80 the relative positions of the material with respect to the perforated floor.

While I have illustrated and described an embodiment of the invention now preferred by me, I do not wish to confine myself 90 specifically thereto except as limited in the following claims.

What I claim, is—

1. In a washing machine, a casing mounted for oscillation, a perforated floor dividing the casing interiorly into a washing chamber and a sump for a washing fluid, means for imparting oscillatory motion to said casing, an impeller blade mounted for swinging movements in said sump, and means to impart swinging movements to said blade simultaneously with and in directions opposite to the movements of the casing. 95

2. In a washing machine, a casing mounted for oscillation, a perforated floor dividing the casing interiorly into a washing chamber and a sump for a washing fluid, an impeller blade mounted for swinging movements in said sump, means to effect the oscillation of the casing, means to impart swinging movements to said blade in directions opposite to the direction of movements of the casing whereby bodies of the fluid are forced alternately upwardly at the front and rear ends of the sump, and baffle devices for causing upwardly moving bodies of the fluid to pass through the floor into said chamber substantially the entire length of the chamber and at opposite sides thereof alternately. 105

3. In a washing machine, an oscillatory casing, a perforated floor dividing the casing interiorly into a material receiving chamber and a sump for a washing fluid, said sump having an arcuate wall, a shaft extending through said sump and mounted in the casing for arcuate movement with the casing, an impeller blade secured to said shaft within the sump, means for imparting oscillatory motion to said casing, the axis of oscillation of the casing being located above the 115

axis of said shaft, and means operatively connected to said shaft and rendered operable by the oscillatory motion of the casing whereby said blade causes the fluid to be forced to and from the sump through different portions of the floor during successive oscillatory movements of the casing.

4. In a washing machine, a casing, a perforated floor dividing the interior of the 10 casing into a washing chamber and a semi-circular sump, said sump being provided in its arcuate wall with a gutter, a shaft extending through said sump axially of the arc of said wall, an impeller blade secured 15 to said shaft and extending radially therefrom, said impeller blade being of less width than the radius of the arcuate wall of the sump, a shoe carried by said blade and serving as a packing therefor with respect to the arcuate wall of the sump, said shoe being arranged for movement radially of the shaft 20 to permit the shoe passing over a foreign article received within said sump, and means operatively connected to the shaft for imparting vibratory motion to said blade.

5. A washing machine comprising a frame, a casing mounted on said frame for oscillatory motion, a perforated floor dividing the interior of the casing into a sump 30 and a washing chamber, a longitudinally disposed wall extending downwardly from said floor at approximately the midwidth of the casing, a baffle provided below the floor at each side of said wall, one of said baffles 35 being located at the front end and the other baffle at the rear end of the casing, means

to impart oscillatory motion to said casing, a shaft extending transversely through said sump, an impeller blade extending radially of said shaft within the sump, a crank arm 40 provided upon said shaft exteriorly of the casing, a crank pin for said crank arm, and a rod connecting the pin of the crank arm to the frame whereby oscillatory movements of the casing will effect vibratory motions to 45 the impeller blade.

6. In a washing machine, a casing, a perforated floor dividing the interior of the casing into a sump and a washing chamber, a longitudinally disposed wall extending 50 downwardly from said floor at approximately the midwidth of the casing, baffles provided below the floor to provide a cavity between the floor and each of said baffles and at each side of said wall, one of said 55 baffles being located at the front end and the other baffle at the rear end of the casing, a shaft extending through the sump at right angles to said wall, an impeller blade carried by said shaft, and means operating through 60 the medium of said shaft to effect vibratory motion to said impeller blade for forcing water into the respective cavities alternately and thence through the floor at opposite sides of said wall.

Signed at Seattle, Washington, this 20th day of March 1924.

SERN P. WATT.
